FLUE DAMPER LATCH

Walter C. Simpson, Oakland, Calif.

Application April 4, 1949, Serial No. 85,457

9 Claims. (Cl. 126—285)

1

The invention relates to a latch for gravity-opened flue dampers.

An object of the invention is to provide a latch of the character described which is automatically controlled entirely by positioning movements of the damper with which it is associated.

Another object of the invention is to provide a flue damper latch which is applicable to damper plates of a usual flat form.

The invention possesses other objects and features of advantage, some of which, with the foregoing, will be set forth or be apparent in the following description of a typical embodiment thereof, and in the accompanying drawings, in which,

Figure 1 is a plan view showing the latch of my invention as operatively applied to the damper of an upright vent pipe of circular cross-section.

Figure 2 is a sectional view taken at the line 2—2 in Figure 1.

Figure 3 is a sectional view corresponding to that of Figure 2, but showing the damper in open position.

Figure 4 is a face view of the inoperatively disposed damper of Figure 3, taken from the bolt-carrying side thereof.

Figure 5 is an enlarged fragmentary perspective view showing the latch operative as in Figures 1 and 2.

Figure 6 is a face view of a flue-mounted latch plate for cooperation with the latch bolt on the damper.

A damper latch embodying my invention has been particularly shown as associated with a flue or vent pipe section 8 having a side wall 9 of circular cross-section. The wall 9 mounts a usual circular damper plate 11 provided with a hinge spindle 12 extending diametrically across it and through complementary bearing openings 13 provided in the wall, the extremities of the spindle 12 beyond the wall 9 being shown as flattened for an operative retention of the spindle with respect to the damper plate and flue wall.

Essentially, the latch of my invention comprises a bolt member 14 hingedly mounted at a central point of the damper plate 11 for swinging in a fixed plane opposite to and spaced from the upper face of the plate, and a catch-plate 15 provided by a member 16 mounted on the flue wall 9

for cooperation with the bolt 14 to releasably support the damper plate 11 in its operative position across the passage of the flue pipe by reason of the engagement of the free end of the bolt in a supporting notch provided by the catch-plate 15.

As particularly illustrated, the latch bolt 14 is mounted on a member 17 having a flat intermediate base portion 18 arranged for fixing to the damper 11 as by rivets 19 applied through the members. The member 17 may be conveniently shaped from a strip of sheet material having portions 21 and 22 correspondingly outstanding from an intermediate portion which comprises the base 18. The portion 21 of the member 17 has a terminal part 21' extending parallel to the base part 18, and the part 21' has one end of the bolt 14 hingedly attached thereto by a hinge pin 23; the present bolt 14 is shown as shaped from a length of round rod having one end flattened and provided with an opening for loosely receiving the attaching hinge pin 23 through it. For a reason to be hereinafter brought out, the bolt 14 has angularly related portions 14' and 14'' lying in a plane perpendicular to the axis of the hinge pin 23.

The portion 22 of the bolt-carrying member 17 is provided with a slot 24 extending across it near its free end, and said slot constantly receives the bolt 14 for a confined movement along it while it is alternately engageable with the upper and lower slot edges by reason of the looseness of its hinging connection at the pin 23. The present slot 24 is symmetrically tapered, with its longitudinal center line in substantially parallel relation to the base 18 at substantially the same distance from the base as the hinged end of the bolt 14. As particularly shown, the bolt 14 is hinged to the part 21' of the member 17 at a point near one side thereof, and the smaller end of the slot 24 is at that end which corresponds to the location of the bolt hinge 23. In mounting the present bolt 14 on the damper, the member 17 is preferably so positioned on the damper that the bolt hinge pin 23 is at, or laterally opposite, the center point of the damper-mounting spindle 12, while a line from the smaller end of the slot 24 to the axis of hinging of the bolt is substantially perpendicular to the axis of hinging of the damper whereby the bolt and its mounting member are carried on a damp-

er half bounded in part by the axis of the spindle 12. Noting that the latch bolt assembly has added an unbalanced weight to the damper half which mounts it, it will be understood that the freed damper will gravitationally assume the position shown for it in Figure 3, and that the bolt 14 will then gravitationally engage the underlying slot end, particularly by reason of the fact that the bend in the bolt 14 extends parallel to the base 18 and toward a line between the bolt pivot and the other slot end; with the described arrangement, the uprightly disposed bolt 14 is arranged to be gravitationally disposed and held against the smaller slot end as is shown in Figure 4.

It will now be seen that the catch-plate 15 has mutually spaced upper and lower portions 15' and 15'' cooperative to provide between them a somewhat zig-zag path in an upright plane and intermediately providing a supporting notch 25 into which the portion of the bolt 14 beyond the slot 24 is laterally movable for securing the damper in its operative position and from which the bolt is removable for releasing the damper for its subsequent inoperative disposal by the action of gravity. The notch 25 is disposed at such a level that the bolt 14 resting therein disposes the damper in its passage-closing relation to the pipe 8 by intermediately engaging the upper edge of the slot 24 to support the underlying weighted half of the damper upon it, as is shown in Figures 1 and 5.

The catch-plate portions 15' and 15'' are particularly shown as comprising mutually coplanar and laterally spaced upper and lower parts of the member 16, said member comprising a flat base portion 26 from which the catch-plate portions 15' and 15'' are supported by flanges 27 and 28 extending transversely from the base 26 at opposite sides thereof. The catch-plate portion 15' extends above an intermediate point of the flange 27 and has a lower edge portion 29 extending obliquely upwardly from the flange to a downwardly directed portion 29' from which an edge portion 29'' continues to the extreme side of the catch-plate portion 15 in generally parallel relation to the edge portion 29, the edge portions 29 and 29' cooperatively providing a downwardly-facing notch 30. The catch-plate portion 15'' extends from the flange 28 below the portion 15', and its upper edge 31 is provided with the upwardly-facing notch 25, the sides of this notch being defined by the top portion of the flange 28 and the upper edge 31 of the portion 15'' extending upwardly from the flange 28 to a point 32 slightly beyond the notch 30 of the catch-plate portion 15', from which point the lower edge 33 of the catch-plate portion extends obliquely in a convex arc to the bottom of the flange 28.

It will now be noted that the portion of the flange 27 below the edge 29 of the upper catch-plate portion 15' is cooperative with the bottom edge 33 to define the adit end of the generally zig-zag path defined between the plate portions 15' and 15'', and that the catch-plate assembly is mounted on the pipe side 9 in such a position that the free end of the damper-carried bolt 14 may be swung upwardly thereinto as the damper assumes a passage-closing position across the pipe 8; the member 16 is suitably fixed to the pipe wall 9 in appropriate position by rivets 26' engaging its base portion 26. A flexible pull cord 34 depends from a point of the damper plate 11 which is at the opposite side of the spindle 12 from the bolt assembly, said cord extending from

an accessible point for its pulling, and being usable to effect a latching and unlatching of the operatively disposed damper in the manner hereinafter described.

When the damper is open, as in Figures 3 and 4, a downward pull on the cord 34 is arranged to rock the damper to and beyond its more-or-less horizontal operative position which is shown for it in Figures 1 and 2 and 5. As the free end of the bolt 14, which is then engaged with the smaller end of the slot 24, moves upwardly in the adit defined between the flange 27 and the edge 33 to engage the lower edge portion 29 of the catch-plate portion 15', it is then laterally engaged and moved by the catch-plate edge 29 into the notch 30 while the bolt is supported from the lower edge of the slot 24 to thereby limit the upward damper movement, and a subsequent release of the cord 34 permits a return swinging of the damper to effect a supported and guided movement of the bolt upon and along the edge 31 into the support notch 25 while the bolt engages the upper sides of the slot 24 for the support of the damper thereat. When the closed damper is to be opened, a pull on the cord 34 is arranged to swing the damper beyond its closed position to release the bolt for its supporting engagement with the upper edge of the slot 24 and to engage the bolt end against the under edge portion 29' of the upper latch plate portion 15' to laterally displace the bolt end beyond the flange 28 whereby a subsequent release of the cord permits a gravity swinging of the damper to its open position and a return of the bolt to its normally inoperative positioning at the smaller end of the slot 24.

In view of the foregoing, it will be understood that the disposal of the latch bolt 14 in the notch 25, and the removal of the latch bolt from said notch, are both effected by successively swinging the damper slightly above its normal operative position by the use of the cord 34 to respectively engage the bolt with the guiding edge portions 29 and 29'' of the catch-plate portion 15'' while it is supported from the damper on the lower edge of the slot 24. With reference to the positioning sliding of the bolt along the catch-plate edges 29 and 31 and 29'', it will be noted that the slope of the bottom edge of the slot 24 facilitates the actions by reducing frictional resistance thereat. Also, since the present latching device lacks any springs in its combination, it is to be particularly noted that it is not subject to the usual operative deterioration of damper latches having spring controls; the present latch control is afforded solely by the cooperation of manual action through the cord 34 and by the action of gravity.

From the foregoing description taken in connection with the accompanying drawings, the advantages of the present flue damper latch will be readily understood by those skilled in the art to which the invention appertains. While I have described the principle of operation, together with a form of my invention which I now consider to comprise a preferred embodiment thereof, I desire to have it understood that the showings are primarily illustrative, and that such changes and developments may be made, when desired, as fall within the scope of the following claims.

I claim:

1. In combination with an upright flue provided with a horizontally hinged damper plate releasably disposable in a predetermined closure plane across the flue, a latch bolt carried by the damper plate within the flue space for swinging adjustment thereon in a fixed path about an axis

transverse to the axis of hinging of the damper plate and between unlatched and latched positions for the bolt with respect to the damper plate, a catch-plate fixed within the flue and providing a rest on which the free end of the bolt is arranged to be seated from above for supporting the damper plate in its said closure plane, and a guide means on the catch-plate provided with downwardly-facing guide faces above the catch-plate rest alternately engageable by said bolt end for respectively shifting the bolt from its unlatched and latched positions with respect to the damper plate over and from over said rest by and upon successive swingings of the damper plate beyond its operative position from its open and closed positions.

2. In combination with an upright flue provided with a horizontally pivoted damper comprising a plate which is disposed in the flue space and is arranged to gravitationally assume its open position and is releasably securable in a predetermined operative position across the flue space, a latch bolt carried by the damper plate within the flue space for swinging adjustment about an axis transverse to the axis of hinging of the damper, and between unlatched and latched positions for the bolt with respect to the damper plate, a member fixed within the flue and providing a rest on which the free end of the bolt is arranged to be disposed for supporting the damper in its operative position, means actuatable to swing the damper from its open position to and beyond its operative position, a guide means mounted on the flue and providing a guide face above the rest provided by the member in the path of the unlatched bolt and engageable thereby to dispose the bolt above the rest by reason of an initial disposal of the damper beyond its operative position by the damper-swinging means for a gravitational damper-supporting seating of the bolt on the rest upon a return movement of the damper, and a guide means providing a guide face above the rest provided by the member in the path of the latched bolt and engageable thereby to dispose the bolt from over the rest to free the damper for its gravitational return to its open position by reason of a succeeding disposal of the damper beyond its operative position by the damper-swinging means.

3. A structure in accordance with claim 2 whereof the rest-providing member provides both said guide faces.

4. In combination with an upright flue provided with a pivoted plate comprising a damper which is disposed in the flue space and is arranged to gravitationally assume its open position and is releasably disposable in a predetermined operative position with respect to the flue, a latch bolt carried by the damper within the flue space for swinging in a fixed path opposite the damper and about an axis transverse to the axis of hinging of the damper and between unlatched and latched positions for the bolt with respect to the damper, a catch-plate fixed within the flue and providing a rest on which the free end of the bolt is arranged to be disposed for supporting the damper in its operative position when in latching position with respect to the damper, a pull member actuatable to swing the damper from its open position to and beyond its operative position, a first guide means fixed within the flue and providing a guide face above the catch-plate rest which is engageable by said bolt by reason of the disposal of the damper beyond its operative position to position

the bolt above the rest for its seating thereon when the damper-swinging pull member is released, and a second guide means fixed within the flue and providing a guide face above the catch-plate rest which is engageable by said bolt by reason of the disposal of the damper beyond its operative position to dispose the seated bolt from over said rest to permit a gravity return of the damper to its open position when the damper-swinging pull member is released.

5. A structure in accordance with claim 4 whereof the first guide face faces downwardly and slopes upwardly from a point in the path of upward movement of the unlatched bolt to a stop positioning the engaged bolt above the seat.

6. A structure in accordance with claim 4 whereof the second guide face faces downwardly and is inclined to the closure plane of the damper and extends above and from over the rest for cooperation with the bolt to dispose the bolt from over the rest and in unlatched position with respect to the damper when the damper-swinging means is actuated to swing the damper to engage the bolt with said face.

7. In a flue provided with a damper which is hingedly supported for swinging about a horizontal axis and is arranged to normally hang upright in inoperative position in the flue passage, a latch-bolt carried by the damper for swinging in a fixed path opposite the damper and about an axis transverse to the axis of hinging of the damper and between unlatched and latched positions of the bolt with respect to the damper for its gravity disposal in a predetermined unlatched position with respect to the damper when the same is upright and for its frictional engagement with the damper when the same is swung from its upright position in a closing movement thereof, a catch member fixedly mounted on the flue and providing a rest arranged for engagement by the latch bolt to support the damper in its operative position, and a guide member mounted on the flue and providing first and second inclined guide faces above the catch member rest engageable by the bolt to respectively guide the latter into and out of disposal above the rest solely by reason of successive swinging movements of the damper beyond its operative position, the first said guide face extending across the path of movement of the bolt with the closing damper while the bolt is disposed in its unlatched position with respect to the damper.

8. In a flue provided with a damper which is hingedly supported for swinging between operative and inoperative positions thereof about a horizontal axis and is arranged to normally hang upright in the flue passage, a latch bolt carried by the damper for swinging in a fixed path opposite the damper and about an axis transverse to the axis of hinging of the damper and between unlatched positions at opposite sides of a latching position of the bolt with respect to the damper for its gravity disposal in one said unlatched position with respect to the damper when the same is swung from its upright position, a catch member fixedly mounted on the flue and providing an upwardly-facing seat arranged for damper-supporting engagement by the latch bolt, and a guide member fixedly mounted on the flue and providing downwardly-facing similarly-inclined first and second guide faces above the catch member seat cooperative with the positioned bolt to respectively guide the latter into and out of a position above the seat solely by

reason of successive swinging movements of the damper beyond its operative position to engage the bolt with the respective guide faces, the first said guide face extending across the path of upward movement of the bolt in its said unlatched position with respect to the damper as the damper is swung to and beyond its operative position to engage the bolt with this guide face, and the second said guide face extending from over the bolt-receiving seat of the catch plate to 10 dispose the bolt in its other unlatched position with respect to the damper while the bolt is engaged with this guide face.

9. A structure in accordance with claim 8 whereof the seat of the catch member comprises 15 an upwardly-facing notch having a side sloping

to its bottom, and guide faces of the member are downwardly-facing and similarly inclined and are mutually offset to provide a stop face portion connecting them for disposing the engaged bolt above said sloping side of the notch by the action of the first guide face.

WALTER C. SIMPSON.
